(57) **CLAIM**

We claim the ornamental design for a misting fan with spindle shaped enclosure, as shown and described.

DESCRIPTION

FIG. 1 is a right top front corner perspective view of the misting fan with spindle shaped enclosure showing our new design;

FIG. 2 is a left bottom corner perspective view thereof;

FIG. 3 is a front elevation view thereof;

FIG. 4 is a rear elevation view thereof;

FIG. 5 is a left side view thereof;

FIG. 6 is a right side view thereof;

FIG. 7 is a top view thereof; and,

FIG. 8 is a bottom view thereof.

The broken line showing the blade and hand trigger forms no part of the claimed design.
